UNITED STATES PATENT OFFICE.

JOHN BOULTBEE BROOKS, OF BIRMINGHAM, ENGLAND.

CYCLE-SADDLE.

SPECIFICATION forming part of Letters Patent No. 600,402, dated March 8, 1898.

Application filed April 7, 1897. Serial No. 631,186. (No model.) Patented in England June 30, 1896, No. 14,407; in France March 20, 1897, No. 265,198, and in Germany March 20, 1897, No. 20,523.

To all whom it may concern:

Be it known that I, JOHN BOULTBEE BROOKS, manufacturer, a subject of the Queen of Great Britain, residing at Criterion Works, Great 5 Charles street, in the city of Birmingham, England, have invented certain new and useful Improvements in Cycle-Saddles, of which the following is a specification, and for which invention I have obtained Letters Patent in 10 Great Britain, dated June 30, 1896, No. 14,407; in France, dated March 20, 1897, No. 265,198, and in Germany, dated March 20, 1897, Serial No. B 20,523.

This invention relates to the under or supporting framings of cycle-saddles, and has for 15 its object to provide a non-tucking seat, or a seat which yields and becomes soft on downward pressure being applied thereto by the weight of a rider, and this is accomplished 20 by the employment, in conjunction with the framing, of a pair or two pairs of separated stretcher arms or links, the inner ends of the said links being jointed to the base framing, bracket, or support, while their outer ends 25 are jointedly connected at separated points one above another to fixed hanging brackets or rods or their equivalents made fast to the underside of the back ends of the seat through the medium of the back plate or otherwise. 30 The peak end of the seat may be made fast to an under plate carried by the fixed supporting bracket or base framing, between whose rear or outer ends or cross-extensions of them and the back plate pillar coiled or 35 other springs may be interposed and thus support the rear end of the seat.

Figure 1 of the accompanying drawings represents partly in side elevation and partly in vertical section a cycle-saddle with the under 40 framing and its cognate parts constructed, arranged, and operating in accordance with my invention. Fig. 2 represents an under side plan of the said saddle with portions in section. Fig. 3 represents a like sectional view 45 as Fig. 1, but with the whole of the parts in elevation other than the seat and back plate, but with the springs compressed and the back of the seat depressed, slightly slackened, and rendered soft. The dotted lines represent the 50 position from which the seat has descended.

Fig. 4 is a back view of the saddle with the parts in the same positions as represented in Fig. 1. Fig. 5 represents a back elevation of the saddle with the parts in the same positions as represented in Fig. 3. Fig. 6 represents a sectional view of the back part of the saddle. Fig. 7 represents a view of the saddle, showing the bracket or under supporting-framing and coiled springs removed, leaving only the depending vertical rods and stretcher 60 and connecting links, which are shown in section. Fig. 8 is an elevation of the back end of the saddle with the seat in section and the springs removed.

The same letters of reference indicate corresponding parts in the several figures of the drawings.

Directed from front to back of the under side of the leather seat *a* of the saddle is a rigid under framing *b*, composed of two sides 70 *b'*, with the fore-end parts *b*² riveted or otherwise made fast to and perfectly rigid with the peak-plate *c*, carried underneath the peak *a'* of the seat *a*, and passing through the bracket *c'* of the said peak-plate is an adjustable tension-screw *d*. The back end *a*² of the said seat is made fast to and rigid with depending rods or hanging lever-brackets *e* through or by means of the back or skirting plate *e'*, which is made fast to the back of the seat by 80 riveting or the like, and also carries studs *e*² for receiving the upper ends of the springs *f*, located between the said back plate and cross extensions or rests *b*³ of the tie-bar *b*⁵, bracing together the rear or after ends *b*⁴ of the 85 bracket sides *b'*. The stand side or lower ends *f'* of the springs take around the studs *b*⁶ and rest upon the top sides of the cross extension or rests *b*³, so that the compression of the springs occurs between the under side of the seat and 90 fixed rests *b*³, which latter always remain quiescent, as it is kept immovable by the lug *g*, attached to a seat support or pillar.

h h' are two pairs of parallel and separated seat-stretcher or connecting arms or links located upon the two opposite sides *b*⁴ of the after end of the rigid frame *b* and jointedly connected thereto at their inner ends by rivets or pins *i* and at their outer ends to the lower parts *e*³ of the depending rods or hanging 95 100

brackets *e* by loose rivets *c*⁴, about which the said arms or links turn as centers alike unto the other ends.

Operation: In this form of my invention 5 the saddle and its parts normally take the positions represented in Fig. 1, with the seat *a* held taut through the agency of the stretcher-links, which are kept nearly in a right line with the framing by the expansion of the 10 springs acting upon the under side of and lifting the said seat. Thus when the stretcher-rods are in nearly a straight line or nearly at a right angle with the depending rods, which always remain in a constant vertical plane, 15 then the seat is kept taut. Now immediately a seat becomes weighted by a rider then the back end of the saddle is depressed, turning upon the leather at the peak end as a center, compressing the springs *f*, and lowering the 20 depending brackets *e*, which take with them the outer ends of the stretcher-links *h h'*, which are turned at an angle upon their joint centers *i* into a less depressed position to that represented in Fig. 3, but more depressed 25 than in Fig. 1, whereby the extreme tension of the seat is slightly slackened and a comfortable softness without tucking is attained; but it is obvious that should the machine suddenly jolt the back of the seat might be lowered to its fullest extent and compress the 30 springs and depress the links to the position shown in Fig. 3, which further slackens the seat, and hence a desirable and increased softness for neutralizing concussion incidentally 35 occurs. On relieving pressure the springs, assisted to a small extent by the flexibility

of the seat, take the parts back to their normal positions, with the seat-leather fully stretched.

Having fully described my invention, what 40 I desire to claim and secure by Letters Patent is—

1. The combination with the saddle and its supporting-frame, of parallel stretcher-links disposed one above the other and pivotally 45 connected at their forward ends to said supporting-frame, rigid brackets or rods depending from the rear of the saddle and pivotally attached to the rear ends of the parallel stretcher-links, and springs arranged between 50 the rear of the saddle and saddle-frame, substantially as described.

2. The combination with the saddle-supporting frame, of the saddle attached at its peak to a fixed support carried by the supporting-frame, parallel stretcher-links disposed one above the other and pivotally connected at their forward ends to said supporting-frame, rigid brackets or rods depending from the rear of the saddle and pivotally attached to the rear ends of the parallel stretcher-links, and springs arranged between the 55 rear of the saddle and saddle-frame, substantially as described.

In testimony whereof I have hereunto set 60 my hand in presence of two subscribing witnesses.

JOHN BOULTBEE BROOKS.
